United States Patent

Des. 241,554
Patented Sept. 21, 1976

241,554

SPEAKER ENCLOSURE

Jose Juan Bertagni, Newport Beach, and Haskell M. Metz, Laguna Beach, Calif., assignors to Bertagni Electro-acoustic Systems Inc., Costa Mesa, Calif.

Filed Aug. 13, 1975, Ser. No. 604,449

Term of patent 14 years

Int. Cl. D14—01

U.S. Cl. D26—14 G

FIG. 1 is a front elevational view of the speaker enclosure of the present invention;

FIG. 2 is a side elevational view of the speaker enclosure;

FIG. 3 is a rear elevational view of the speaker enclosure; and

FIG. 4 is a top plan view of the speaker enclosure.
We claim:

The ornamental design for a speaker enclosure, substantially as shown and described.
